UNITED STATES PATENT OFFICE

165,913

COIN HOLDER

Joseph Goodman, New York, N. Y.

Application December 7, 1950, Serial No. 13,324

Term of patent 3½ years

(Cl. D87—3)

To all whom it may concern:

Be it known that I, Joseph Goodman, a citizen of the United States and a resident of county of Bronx, city and State of New York, have invented a new, original, and ornamental Design for a Coin Holder, of which the following is a specification, reference being had to the accompanying drawing, forming a part thereof.

On the drawing:

Figure 1 is a top view of a coin holder with a chain represented in broken lines, showing my new design;

Figure 2 is a front view with a portion of the chain shown in broken lines;

Figure 3 is a bottom view;

Figure 4 is a front view in elevation of the coin holder as shown in Figure 3; and

Figure 5 is a left hand end elevation of Figure 3. The essential features of the design are shown in full lines.

I claim:

The ornamental design for a coin holder, as shown and described.

JOSEPH GOODMAN.
